BY Victor J. Evans

ATTORNEY

UNITED STATES PATENT OFFICE.

CHARLES EDWIN WELCH, OF WACO, TEXAS.

HOLDER.

Application filed February 9, 1924. Serial No. 691,839.

This invention relates to improvements in roll holders especially adapted to hold rolled toilet paper.

An object of the present invention is the provision of a roll holder having rigid arms for supporting the roll and arranged so that the said roll may be placed in position without spreading or springing the arms, so that the latter will always remain in proper relative relation to hold the roll against accidental displacement.

With the above and other objects in view, the invention further includes the following novel features and details of construction, to be hereinafter more fully described, illustrated in the accompanying drawings and pointed out in the appended claim.

In the drawings:

Figure 1 is an elevation of a roll holder with a roll of paper shown in position thereon.

Figure 2 is a top plan view showing by dotted lines the manner of positioning the roll.

Referring to the drawings in detail wherein like characters of reference denote corresponding parts, the invention is shown as comprising a yoke which is formed preferably of heavy wire and bent to provide spaced parallel arms 11 which are connected at one of their ends by means of a bar 12. The free ends of the arms 11 are provided with oppositely disposed inwardly extending aligned bearing ends or trunnions 13 which are adapted to enter the opening 14 of a paper roll 15.

In devices of this character it is usually necessary to spring the arms apart to insert the trunnions within the opening of the roll.

After a short use, the arms lose their resiliency and fail to resume their proper position, so that they will not effectually hold the paper in place.

This is overcome in the present invention by providing one of the arms 11 at its junction with the trunnion 13, with an inwardly

extending right angled offset portion 16. This end of the arm 11 may be inserted within the opening 14 of the roll as shown by the dotted lines in Figure 2 and the said roll swung inward so that the opposite trunnion 13 will enter the opposite end of the opening. Thus, the roll may be positioned without springing or spreading the arms and the yoke may be formed of rigid or non-yieldable material. When in position, the roll 15 will receive the trunnions 13 and will be positioned between one of the arms 11 and the portion 16' of the right angled portion so as to act as a guide for the roll.

The yoke is supported by any suitable means, such as a plate 18 and the latter may be provided with spring tongues 19 which receive the bar 12. The plate is provided with openings 20 for the passage of fastening devices.

When positioning the roll 15, the yoke is arranged horizontally or at right angles with respect to the plate 18 and in order to hold the yoke in this position, the bar 12 is provided with an offset portion 21 so that it binds within the spring tongues 19 and will be thus yieldingly held for convenient positioning of the roll.

The invention is susceptible of various changes in its form, proportions and minor details of construction and the right is herein reserved to make such changes as properly fall within the scope of the appended claim.

Having described the invention what is claimed is:—

A roll holder comprising a substantially yoke-shaped member including spaced parallel arms, a bar connecting said arms, spaced aligned roll supporting trunnions at the opposite ends of the arms, an inwardly extending right angled offset portion joining one of the arms and its trunnion and means for supporting the yoke-shaped member.

CHAS. EDWIN WELCH.
